CONDUCTING CHEMICAL REACTIONS IN
ALKALINE MEDIA

John J. Grebe and John H. Reilly, Midland,
Mich., assignors to The Dow Chemical Com-
pany, Midland, Mich., a corporation of
Michigan

No Drawing. Application March 6, 1930.
Serial No. 433,807

2 Claims. (Cl. 260—154)

This invention relates to methods for conducting chemical reactions in alkaline media at elevated temperatures and pressures, and has for a particular object the prevention of stoppages in steel tubular reaction coils, such as are often utilized in such reactions, due to the building up therein of a scale or incrustation of crystallized products such as magnetic iron oxide. Other objects will appear as the description proceeds.

An example of an organic chemical reaction of the aforesaid character is found in the well known process for the manufacture of a phenol by hydrolyzing a halogenated aromatic hydrocarbon wherein the latter is heated under pressure with an aqueous caustic alkali solution. When chlorobenzene and caustic soda are employed for the specific reactants the reaction is carried out at a temperature between about 300° and 400° C., preferably between 350° and 390° C. On account of the high pressure developed at the reacting temperature, between 3000 and 5000 pounds per square inch, the process is most advantageously carried out in a tubular type of autoclave comprising steel pipe coils. The caustic alkali solution at the high temperature to which it is heated attacks the steel coils and dissolves iron from the exposed surfaces thereof. When the reaction mixture is cooled down prior to discharge from the tubular system, the dissolved iron is precipitated out as magnetic iron oxide, Fe_3O_4 . This oxide forms as a hard, coherent scale or incrustation which builds up in the tubes, causing obstruction and eventual stoppage. This latter circumstance greatly shortens the useful life of the tubes, necessitating frequent repairs and renewals, and also gives rise to the danger of blowouts whenever stoppage occurs.

We have now found that the building up of the aforesaid incrustation of magnetic iron oxide may be substantially completely prevented by adding to the reaction mixture a small amount of a colloidal material, such as soap, which is capable of withstanding the reaction conditions without decomposition. The invention, then, consists of the method hereinafter fully described and particularly pointed out in the claims, the following description setting forth but a few of the various ways in which the principle of the invention may be practiced.

Under actual operating conditions for the manufacture of phenol by the foregoing process as found in plant practice, the tubular system consists of three sections or zones, the first being the preheating zone, the second the reacting zone

and the third the cooling zone. In the preheating zone the mixture of caustic soda solution and chlorobenzene is heated up to about 350° C. whereat the reaction proceeds at a suitable rate. In this zone the alkali solution attacks the iron surface exposed thereto and dissolves off some of the iron until the solution becomes saturated therewith. Due to such continuous attack and gradual dissolution of the metal of the tubes, the life of the latter is limited, but in general ordinary steel tubes may be kept in service for about 300 hours before the wall thickness has been reduced to the limit of safety. By utilizing certain corrosion-resistant alloy steels, however, a longer life for the tubes may be attained. Within the reaction zone the attack upon the steel tubes almost ceases, owing to the solution having become substantially saturated with respect to the iron compound before arriving in the latter zone. Toward the end of the zone, however, where the temperature begins to drop, there is a tendency for some of the dissolved iron compound to be precipitated out and deposited upon the tube walls as a hard, adherent scale of magnetic iron oxide, which gradually builds up and constricts the bore of the tube until its use must be discontinued in order to avoid danger of complete stoppage. It has been found that the tubes may be used about 1000 hours in the last half of the reaction zone before the condition just mentioned becomes such that replacement may be necessary. In the cooling zone, however, where the temperature of the hot mixture is reduced from about 350° to as low as 100° C. the deposition of iron oxide scale occurs much more rapidly, at times necessitating replacement of the tubes after as little as about 200 hours use. The scale may be removed more or less completely from used tubes by suitable treatment, but this involves disassembling the apparatus and considerable expense is incurred in the handling. The tubes likewise deteriorate rapidly under such treatment, and can safely be refitted for service only two or three times, after which they must be discarded. The necessity for frequent replacement and renewal of tubes places a heavy burden of expense upon the process.

We have now found that the deposition of magnetic iron oxide scale in the tubes in the reacting and cooling zones may be substantially prevented by introducing into the reaction mixture a colloidal substance stable under the conditions existing in the process, which has the effect of inhibiting grain growth of the precipitated iron oxide. The action of the colloid may consist simply in inter-

posing a film between the individual particles of precipitated iron oxide which prevents their cohesion or agglomeration into larger masses and the building up into a hard scale, or the colloid 5 may serve as a dispersing or deflocculating agent to reduce the size of particles and prevent their coalescence. The result in either case is that the black iron oxide is precipitated in a highly dispersed form which is carried along by the stream 10 of liquid in the tubes and is discharged from the apparatus admixed with the reaction product.

As a suitable colloid for introducing with the reaction mixture we have found soap to be particularly effective, although other colloids and 15 peptizers such as sodium tartrate, chromic oxide, saponin, tannin, glycerine or glucose, have also been used with beneficial results. The invention is not restricted to any particular kind of soap, and in general the choice will be determined by 20 the cost. We have employed, in addition to ordinary soap made by the saponification of animal or vegetable fats, the alkali salts of the fatty acids, such as sodium oleate or sodium stearate, with equal advantage. The amount of soap or 25 other colloid to be added is about 0.025 to 0.1 per cent of the solids present, although somewhat more or less may be employed without materially changing the result. It is sufficient to provide enough of the soap to mix with the precipitated 30 black iron oxide and prevent crystal growth, and in practice the amount above mentioned has been found ample. The concentration of the caustic alkali solution may be varied within wide limits without affecting the action of the soap.

35 When strong alkali solutions, i. e. about 30 to 40 per cent., are employed, however, there is an added advantage from using the soap, since at such concentration some of the salt formed in the reaction is crystallized out and the crystals have 40 been found to exert a scouring or eroding action on the tubes due to the high velocity of flow therein. In the presence of soap or similar colloid, however, crystal growth is impeded or inhibited just as with the magnetic iron oxide, the size of 45 the precipitated particles is kept small and a crystal sludge of soft consistency is formed which does not abrade the tube walls as greatly as the larger crystals otherwise formed.

50 By means of the improved procedure hereinbefore described it is possible substantially to prevent scaling and incrustation of the tubes in the reacting and cooling zones so that their life is increased almost indefinitely. The savings thereby effected are of material consequence in a commercial process, since not only is the frequent renewal of tubes largely eliminated but also delays 55 any interruption of process incident thereto.

60 The separation of the magnetic iron oxide sludge from the reaction product may be carried out by usual means, such as filtration, or by distilling off volatile products whereupon the sludge remains in the still residue.

65 While our invention has been described illustratively by reference to the manufacture of phenol by reacting chlorobenzene and an aqueous

caustic soda solution, it is broadly applicable to similar processes for the manufacture of phenolic compounds by reaction of a hydrolyzable substituted derivative of an aromatic hydrocarbon, e. g. a halogenated or sulphonated aromatic hydrocarbon, and an aqueous caustic alkali solution at an elevated temperature and pressure. The invention still further is adapted for use in any chemical process wherein an aqueous caustic alkali solution is heated under pressure in a 10 tubular or other form of autoclave. While greater advantage attaches to the use thereof in operations carried out in tubular apparatus, due to the greater readiness with which passages of 15 relatively small bore may be obstructed or stopped up completely, there is also advantage when used with other types of pressure apparatus, the operation of which may be deleteriously affected by the accumulation on the walls thereof of a hard, impervious, heat-insulating scale which may 20 interfere with the transfer of heat or give rise to mechanical difficulties in the use of the apparatus.

25 The term "dispersing agent" employed in certain of the following claims is understood to include a soap or other stable colloid or peptizing agent comprised within the group of compounds hereinbefore specifically mentioned or the equivalent thereof.

30 Other modes of applying the principle of our invention may be employed instead of the one explained, change being made as regards the method herein disclosed, provided the step or steps stated by any of the following claims or the equivalent of such stated step or steps be employed.

35 We therefore particularly point out and distinctly claim as our invention:—

1. In a method of preparing phenol by heating under pressure at a temperature between 300° 40 and 400° C. in contact with surfaces of ferrous metal a reaction mixture comprising chlorobenzene and aqueous sodium hydroxide solution, the improvement which consists in adding to the said reaction mixture a relatively small amount 45 of a soap, whereby to prevent the formation on the walls of the reaction vessel of a hard adherent scale of magnetic iron oxide formed by chemical action between the aqueous alkali and the iron container for the said reaction mixture. 50

2. In a method of preparing phenol by heating under pressure at a temperature of between 300° and 400° C. in contact with surfaces of ferrous metal a reaction mixture comprising chlorobenzene and aqueous sodium hydroxide solution, the 55 improvement which consists in adding to the said reaction mixture up to 0.1 per cent of a soap, whereby to prevent the formation on the walls of the reaction vessel of a hard adherent scale of magnetic iron oxide formed by chemical action 60 between the aqueous caustic alkali and the iron container for the said reaction mixture.
